UNITED STATES PATENT OFFICE

140,673

DESIGN FOR A BUTCHER'S SANITARY TOOL RACK OR SIMILAR ARTICLE

Alfred H. Remillong and Wayne E. Montandon, Eugene, Oreg.

Application August 23, 1944, Serial No. 114,980

Term of patent 14 years

(Cl. D44—29)

To all whom it may concern:

Be it known that we, Alfred H. Remillong and Wayne E. Montandon, both citizens of the United States, both residing at Eugene, in the county of Lane and State of Oregon, have invented a new, original, and ornamental Design for a Butcher's Sanitary Tool Rack or Similar Article, of which the following is a specification, reference being had to the accompanying drawing, forming a part thereof.

butcher's sanitary tool rack, showing our new design;

We claim:

The ornamental design for a butcher's sanitary tool rack or similar article, as shown.

ALFRED H. REMILLONG.
WAYNE E. MONTANDON.
